UNITED STATES PATENT OFFICE.

WILLIAM S. GUBELMAN, OF BUFFALO, NEW YORK, ASSIGNOR TO JOHN C. CONWAY, OF SAME PLACE.

DESIGN FOR A BICYCLE-HUB.

SPECIFICATION forming part of Design No. 33,870, dated January 8, 1901.

Application filed November 26, 1900. Serial No. 37,833. Term of patent 7 years.

To all whom it may concern:

Be it known that I, WILLIAM S. GUBELMAN, a citizen of the United States, residing at Buffalo, in the county of Erie and State of New York, have invented and produced a new and original Design for Bicycle-Hubs, of which the following is a specification, reference being had to the accompanying drawings, forming a part thereof.

10 This design relates to the shape or configuration of wheel-hubs for bicycles and other velocipedes.

In the accompanying drawings, Figure 1 is a side elevation of a bicycle-hub embodying 15 my design. Figs. 2 and 3 are perspective views of the hub viewed from opposite ends thereof.

Like letters of reference refer to like parts in the several figures.

20 The leading feature of my design consists of a cylindrical barrel or hub-body provided near one end with an annular enlargement or casing having the form of two truncated cones placed base to base and meeting in 25 an annular rim which projects beyond said cones.

Referring to the drawings, A is the cylindrical body of the hub.

a is a projecting annular flange arranged at one end of the hub-body, and a' a similar 30 perforated flange arranged near the opposite end thereof.

B is the projecting annular casing or enlargement arranged on the hub-body near the end thereof which has the flange a. 35 This enlargement has an inner vertical side, as shown at b, and an open outer side and is provided centrally with a projecting annular rim b' containing openings b². The marginal portions b³ of this enlargement converge 40 toward the rim b', so that the casing has the form of two truncated cones placed base to base and meeting in a projecting annular rim.

What I claim is—

The design for a bicycle-hub, substantially 45 as herein shown and described.

Witness my hand this 31st day of October, 1900.

WILLIAM S. GUBELMAN.
